UNITED STATES PATENT OFFICE.

JOHN I. BELLAMY, OF CHICAGO, ILLINOIS, ASSIGNOR TO AUTOMATIC ELECTRIC COMPANY, OF CHICAGO, ILLINOIS, A CORPORATION OF ILLINOIS.

MAKE-BUSY ARRANGEMENT FOR SECONDARY TRUNKING SWITCHES.

Application filed August 25, 1922. Serial No. 584,218.

To all whom it may concern:

Be it known that I, JOHN I. BELLAMY, a citizen of the United States of America, and a resident of Chicago, Cook County, and 5 State of Illinois, have invented certain new and useful Improvements in Make-Busy Arrangements for Secondary Trunking Switches, of which the following is a specification.

10 The present invention relates to make busy arrangements for secondary trunking switches, but is concerned more particularly with secondary trunking systems for telephone systems in which a secondary group is 15 made busy immediately upon the last trunk accessible thereto being seized.

This case in some respects is an improvement on a make busy scheme disclosed in the co-pending application of Richardson, serial No. 507,009, filed October 11, 1921.

In order to be able to make a subgroup 25 of secondary switches busy as soon as the last trunk accessible thereto is seized, it has been proposed to arrange the circuits of the secondary switches so that the release trunk conductors of all the idle secondary switches of the sub-group are normally multiplied together and extended to a common relay, which relay is arranged to pull up each time 30 a trunk is seized and to lock to ground when the last trunk accessible to the secondary switches is seized, thereby making the remaining idle secondary switches busy. A circuit which accomplishes this result in the 35 above manner is in many cases objectionable for the reason that, since the release trunk conductors of all the idle secondary switches are multiplied together, the entire sub-group is made busy while one secondary switch 40 therein is hunting for an idle trunk. This feature is rendered less objectionable in the present case by suitably arranging the circuits so that the release trunk conductors of 45 the idle switches are not normally connected together, but are connected together as soon as all the secondary trunks except a small predetermined number become busy. In this way, as many secondary switches as desired 50 may be seized at one time until the number of trunks accessible thereto and remaining idle becomes very small, at which time the release trunk conductors of the idle switches are multiplied together, giving the protection desired by rendering the entire sub-

group of secondary switches busy as soon as 55 the last trunk is taken.

Referring now to the drawings which comprise Figs. 1 and 2, Fig. 1 shows a selector E which has access on one level to the secondary switch C. The secondary 60 switch C has access to the repeater R'. The two conductors extending from the repeater R' are assumed to extend to a distant office and terminate in an incoming selector.

The trunking arrangement perhaps can be 65 understood a little better by referring to Fig. 2, which shows ten selector trunks on the left which extend to ten secondary 70 switches in as many different secondary groups. The third trunk is illustrated as extending to the secondary switch C which is the same switch as shown in Fig. 1. The switch C is shown as having access to ten repeaters, R—R⁹, inclusive, although in practice the number may be either larger or 75 smaller than this. As one instance of the size of the entire secondary group, it may be assumed that there are fifteen groups of selector trunks comprising ten trunks each. One of these groups of selector trunks is 80 shown in Fig. 2, and, as indicated, each selector trunk extends to a separate one of the ten secondary subgroups. The same applies for each of the other fourteen groups of selector trunks. Accordingly, considering 85 any one secondary sub-group, for example, the one in which the secondary switch C is located, there are as many secondary switches as there are groups of selector 90 trunks, namely, fifteen. Accordingly, the 95 multiplying relay 101, Fig. 1, is provided with three armatures 107, 107', and 108, having five working contacts each, making fifteen contacts in all, one for each of the fifteen secondary switches, such as C, in the 95 same sub-group.

In the lower part of Fig. 1, there is shown a group of relays which are the ones which have to do with making the secondary group, in which the secondary switch C is 100 located, busy when the last available trunk is taken.

Perhaps the invention will be understood best if a brief description of the operation of the apparatus shown is given. For this purpose, it will be assumed that the selector E is seized at the terminals 11, 12, and 13. When this occurs, line relay 17 energizes

over conductors 14 and 16, in series with the calling subscriber's loop, and closes a circuit for release relay 18 at armature 28. Release relay 18, upon energizing, opens a point in the circuit of release magnet 24 and prepares a circuit for vertical magnet 22 at armature 30, and at armature 29 places ground on release trunk conductor 15, thereby establishing the usual holding circuit for 10 the switch which seized the selector.

When the calling subscriber operates his calling device in accordance with the first digit of the desired number, the circuit of line relay 17 is opened a corresponding number of times. Each time line relay 17 deenergizes, it sends an impulse of current to vertical magnet 22 by way of armature 30 and its working contact and series relay 19. By the operation of vertical magnet 22, the 20 switch wipers 38—40, inclusive, are raised opposite the desired level of bank contacts. Slow acting series relay 19 is maintained energized in series with vertical magnet 22 throughout the vertical movement and, in conjunction with off normal contacts 26 which close upon the first vertical step, closes a circuit for stepping relay 20 in series with 25 interrupter contacts 27. Relay 20, upon energizing, closes a locking circuit for itself at armature 32, and at armature 33 prepares a circuit for rotary magnet 23.

At the end of the vertical movement, relay 19 deenergizes and closes the circuit of rotary magnet 23. Rotary magnet 23, upon energizing, advances the switch wipers into engagement with the first set of bank contacts in the level opposite which they are raised, and, near the end of its stroke, opens the circuit of stepping relay 20 at interrupter contacts 27. Stepping relay 20, upon deenergizing, opens the circuit of rotary magnet 23 at armature 33, whereupon rotary magnet 23 deenergizes and closes its interrupter contacts 27 again. In case the 40 trunk terminating in the first set of bank contacts is idle, switching relay 21 energizes immediately. Assuming the trunk to be busy, however, switching relay 21 is short circuited by the ground potential which is found on the test contact thereof by test wiper 39 and stepping relay 20 energizes from this same ground, whereupon rotary magnet 23 energizes also and advances the 45 switch wipers into engagement with the next set of bank contacts. This operation continues until an idle trunk is reached, which trunk it will be assumed is the one extending to the secondary switch C. When this occurs, switching relay 21, being no longer short circuited, energizes in series with stepping relay 20, the latter relay not energizing on account of the high resistance of switching relay 21. Upon energizing, switching relay 21 removes ground from armature 28 of line relay 17 at armature 36,

thereby opening the circuit of release relay 18; opens the test circuit and prepares the holding circuit at armature 35, thereby grounding test wiper 39 and making the seized trunk lines busy immediately; and at 50 armatures 34 and 37 disconnects conductors 14 and 16 from the windings of line relay 17 and extends them by way of wipers 38 and 40, bank contacts 41 and 43, conductors 44 and 46, and armatures 64 and 67 and 55 their resting contacts to the winding of line relay 58 and ground, respectively.

Line relay 58 of the line switch C, upon energizing over the calling subscriber's loop, places ground on release trunk conductor 45 at armature 63, thereby establishing the usual holding circuit for the selector E through bank contact 42 and test wiper 39 before release relay 18 has had time to deenergize. As a further result of the energization of relay 58, it closes a circuit for switching relay 59 and stepping magnet 60 in series at armature 62 and at armature 61 connects test wiper 69 to the junction of switching relay 59 and stepping magnet 60. 90 In case the trunk upon which the wipers of the switch are standing is busy, switching relay 59 is short circuited by the ground potential which is present on the test contact thereof and the wipers 68—70, inclusive, are advanced in search of an idle trunk by the buzzer-like action of stepping magnet 60, which magnet operates from ground on the busy test contacts. In the present case, however, it will be assumed that the trunk upon 100 which the wipers of the switch are standing is idle. That being the case, switching relay 59 is not short circuited and, upon energizing in series with stepping magnet 60, which magnet does not energize under these conditions on account of the high resistance of switching relay 59, connects release trunk conductor 45 to the winding of switching relay 59 at armature 66, opens the test circuit and prepares the holding circuit at armature 65, and at armatures 64 and 67 disconnects conductors 44 and 46 from the winding of relay 58 and from ground and extends them by way of wipers 68 and 70, 110 conductors 71 and 73, and the left-hand windings of the repeating coil to the windings of the line relay 80 of the repeater R⁷. Line relay 80, upon energizing, closes a bridge across the outgoing trunk conductors at armature 83, whereupon the distant selector is prepared for operation in the usual manner, and at armature 82 closes a circuit for release relay 81. Release relay 81, upon energizing, short circuits the resistance 86 in the make busy chain circuit at armature 85, 120 and at armature 84 places ground on the release trunk conductor 72, thereby establishing the usual holding circuit for the switches E and C before the slow-acting line relay 58 of the switch C has had time to deenergize. 125

The calling subscriber now operates his calling device in accordance with the remaining digits of the desired number, whereupon line relay 80 of the repeater R' 5 repeats the interruptions of the calling device at armature 83, and the connection is extended to the desired line in the usual manner. When the calling subscriber replaces his receiver upon the termination of 10 the ensuing conversation, line relay 80, upon deenergizing, opens the circuit of the distant line relay at armature 83 and at armature 82 opens the circuit of release relay 81. Release relay 81, upon deenergizing, removes 15 the shunt from around resistance 86 at armature 85 and at armature 84 removes ground from release trunk conductor 72, whereupon switching relays 59 and 21 of the switches C and E deenergize. Switching relay 21 of the selector E, upon deenergizing, closes the usual circuit for release magnet 24 at armature 36, whereupon the selector is restored to normal in the usual manner and the circuit of release magnet 24 20 is again opened at off normal contacts 25.

Referring now to the make busy equipment comprising the relays shown in the lower part of Fig. 1, it will be noted that the release trunk conductors of the idle secondary 30 switches such as C extend to the contacts of relay 101, but are not connected together normally. As the secondary trunks become busy one by one, the resistances such as 86 and 89 are short circuited without producing any particular effect until only two secondary trunks are idle, at which time only two of the resistances will remain unshunted, which resistances it will be assumed are 86 and 89. When this occurs, the marginally adjusted relay 103 energizes and closes 35 a circuit for relay 101 at armature 111. Relay 101, upon energizing, connects the release trunk conductors of all the idle switches in this group together at armatures 107, 107' and 108. This is done so as to force the calls to come into this group one at a time. When the next call comes in, ground 40 is placed on the release trunk conductor of the trunk seized by the seizing switch when the switching relay thereof energizes, such as for example, at armature 35 of switching relay 21 of the selector E. This makes the entire group of switches busy immediately and holds the group busy until the seized 45 secondary switch cuts through and disconnects its release trunk conductor such as for example, at armature 66 of relay 59 of the secondary switch C. When this occurs, the group is rendered idle again. Relay 102 is 50 energized during the time that the secondary switch is hunting but does not have any effect. When the line and release relays of the seized secondary trunk energize, one of the remaining resistances, resistance 86 for example, is short circuited, whereupon the 55 marginally adjusted relay 104 energizes and connects ground to the working contact of armature 109 of relay 102 at armature 112. When the next call comes into this group, 60 which call, of course, takes the remaining idle trunk, ground is thrown forward on the release trunk conductor of the switch seized as described above, and energizes relay 102 as before: Since ground is connected to the working contact of armature 109, relay 102 65 closes a locking circuit for itself at this time, thereby maintaining the release trunk conductors of all idle switches grounded.

As soon as the remaining trunk is seized, the remaining resistance 89 is short circuited, whereupon the marginal relay 105 70 energizes and places a multiple ground on armatures 107, 107' and 108 at armature 113, and at armature 114 closes a circuit for relay 106. Relay 106, upon energizing, closes 75 a locking circuit for itself at armature 116 by way of armature 110 and its working contact, and at armature 115 opens the locking circuit of relay 109, leaving relay 109 energized and the release trunk conductors of 80 the idle switches grounded by way of the working contact of armature 113 and said armature. The circuits remain in this condition until one secondary trunk becomes 85 idle. When this occurs, relay 105 falls back; 90 opens the initial circuit of relay 106 at armature 114; and at armature 113 opens the circuit of relay 102 and renders the group 95 available again. Relay 102, upon deenergizing, opens a point in its previously closed 100 locking circuit at armature 109, and at armature 110 opens the circuit of relay 106. Relay 106, upon deenergizing, prepares the locking circuit of relay 102 at armature 115.

In case the remaining trunk is seized, relay 105 pulls up again with the hereinbefore described results, or in case another trunk becomes idle before the remaining trunk is seized, relay 104 deenergizes when the shunt is removed from around another of the chain resistances, such as 86 or 89. Upon deenergizing, relay 104 opens a point in the locking circuit of relay 102 at armature 112.

In case still another trunk becomes idle, relay 103 deenergizes and opens the circuit 115 of relay 101 at armature 111, whereupon the various release trunk conductors of the idle switches in this group are separated at armatures 107, 107' and 108.

What is claimed is:

1. In a telephone trunking system, a plurality of incoming trunks, each trunk terminating in a switching mechanism, a lesser plurality of outgoing trunks accessible in common to all said mechanisms, each of said incoming trunks having a test conductor, said conductors being disconnected from each other, and means effective whenever there are only a predetermined number of outgoing trunks idle for connecting together 125 130

- the test conductors of all the idle incoming trunks.
2. In a telephone trunking system, a plurality of incoming trunks, each terminating in a switching mechanism, a lesser plurality of outgoing trunks accessible in common to all said mechanisms, each of said incoming trunks having a test conductor, said conductors being disconnected from each other, means effective whenever there are only a predetermined number of outgoing trunks idle for connecting together the test conductors of all the idle incoming trunks, and means effective whenever there is only one idle outgoing trunk for placing a guarding potential on the test conductors of all the idle incoming trunks when the next incoming trunk is taken for use.
3. In a primary and secondary telephone trunking system in which the remaining idle primary trunks are all rendered non-selectable immediately upon seizure of any primary trunk when there is only one secondary trunk available, and in which the primary trunks are kept busy until another secondary trunk becomes available, a test conductor for each primary trunk, said conductors being disconnected from each other, and means under the control of the secondary trunks for connecting together all test conductors of the idle primary trunks whenever there are only a predetermined number of secondary trunks remaining idle.
4. In a make busy circuit, three relays, a circuit therefor, a group of trunks, and means controlled over said trunks for operating the first of said relays whenever only two of said trunks are idle, for operating the second of said relays whenever only one of said trunks is idle, and for operating the third of said relays whenever none of said trunks are idle.
5. In a telephone system, means for busy-ing automatic switches comprising a circuit, a series of resistances included in said circuit, means for separately short circuiting said resistances, a relay in said circuit responsive to the short circuiting of all said resistances except one, and another relay in said circuit responsive only to the short circuiting of all said resistances.
6. In a telephone system, means for busy-ing automatic switches comprising a circuit, a series of resistances included in said circuit, means for separately short circuiting said resistances, a relay in said circuit responsive to the short circuiting of all said resistances except two, and another relay in said circuit responsive only to the short circuiting of all said resistances.
7. In a telephone system, means for busy-
- ing automatic switches comprising a circuit, a series of resistances included in said circuit, means for separately short circuiting said resistances, a relay in said circuit responsive to the short circuiting of all said resistances except two, a second relay in said circuit responsive to the short circuiting of all said resistances except one, and a third relay in said circuit responsive only to the short circuiting of all said resistances.
8. In a telephone system, a group of switches, release trunk conductors terminating in said switches, trunk lines accessible to said switches, and means responsive to the busy condition of a predetermined number of said trunk lines for connecting the release trunk conductors associated with idle ones of said switches together.
9. In a telephone system, a group of switches, release trunk conductors terminating in said switches, trunk lines accessible to said switches, and means responsive when all but two of said trunk lines become busy for connecting together all of said release trunk conductors except those associated with busy switches.
10. In a telephone system, a group of switches, release trunk conductors terminating in said switches, trunk lines accessible to said switches, relay mechanism for connecting together the release trunk conductors associated with idle ones of said switches, and circuit arrangements whereby said mechanism is placed under the joint control of a plurality of said trunk lines.
11. In a telephone system, a group of automatic trunking switches, a group of trunk lines accessible to said switches, a circuit for rendering all idle switches busy responsive to the seizure of one of said switches, and means for closing said circuit only when a given plurality of said trunk lines are in use.
12. In a telephone system, a plurality of incoming trunks each terminating in a switching mechanism, a lesser plurality of outgoing trunks accessible in common to all said mechanisms and means for busying the excess incoming trunks when the outgoing trunks are all in use, said means including three relays, with means for energizing one relay when all but two of said outgoing trunks are busy, means for energizing another of the relays when all but one of said outgoing trunks are busy, and means for energizing the other relay when all of said outgoing trunks are busy.
- In witness whereof, I hereunto subscribe my name this 21st day of August, A. D., 1922.

JOHN I. BELLAMY.
